(57) CLAIM

We claim the ornamental design for the retail merchandise display strip, as shown and described.

DESCRIPTION

FIG. 1 is a perspective view of the retail merchandise display strip:

FIG. 2 is a partial perspective view thereof;

FIG. 3 is a top view thereof;

FIG. 4 is a bottom view thereof;

FIG. 5 is a front view thereof;

FIG. 6 is a back view thereof;

FIG. 7 is a side view thereof

FIG. 8 is a side view thereof showing the side opposite that shown in FIG. 7;

FIG. 9 is another perspective view thereof, exposing a side opposite that shown in FIG. 1; and,

FIG. 10 is another perspective view thereof.

The use of broken lines in the aforementioned figures is for illustrative purposes only. The features shown in broken lines form no part of the claimed design.

1 Claim, 6 Drawing Sheets
